UNITED STATES PATENT OFFICE.

MARTIN O. REHFUSS AND JOHN GEORGE REHFUSS, OF PHILADELPHIA, PENNSYLVANIA, ASSIGNORS TO THE CURTIS PUBLISHING COMPANY, OF PHILADELPHIA, PENNSYLVANIA, A CORPORATION OF PENNSYLVANIA.

PACKAGE-TWINE-FASTENING MACHINE.

1,183,236.

Specification of Letters Patent. Patented May 16, 1916.

Application filed May 22, 1915. Serial No. 29,846.

To all whom it may concern:

Be it known that we, MARTIN O. REHFUSS and JOHN GEORGE REHFUSS, both citizens of the United States, and residents of Philadelphia, in the county of Philadelphia and State of Pennsylvania, have jointly invented a certain new and useful Package-Twine-Fastening Machine, of which the following is a specification.

10 The present application covers a portion of the machine shown and described in our Patent No. 1,164,548, granted Dec. 14, 1915, together with improvements.

15 The principal objects of the present invention are to provide efficient and reliable mechanism for clenching a staple around the twine with which a package is tied, so as to firmly secure it; to provide the mechanism with efficient means for making the staples 20 from a length of wire intermittently fed to the machine; to provide for properly presenting the twine to the stapling mechanism in such a way that the staple can be reliably clutched around the twine; to provide for 25 cutting the cord or twine in a plane at right angles to itself, so that its end will be in proper condition to permit of its being threaded, and to provide a machine for automatically clenching a staple around a twine 30 or cord which encompasses a package in such a way that the fastening is tight and the outside of the package or paper applied thereto is not marred or disfigured.

35 The invention will be claimed at the end hereof, but will be first described in connection with the embodiment of it chosen from among other embodiments for illustration in the accompanying drawings, in which—

Figure 1, is a front view, partly in section, 40 of a machine embodying features of the invention with parts thereof omitted in order to illustrate more particularly the stapling mechanism. Fig. 2, is a side view, partly in section, of Fig. 1. Fig. 3, is a top or plan view. Fig. 4, is a perspective view showing the stapling mechanism as viewed from the rear. Fig. 5, is a view similar to Fig. 4 showing another position of the parts. Fig. 6, is a view of the stapling and cutting 45 mechanism taken from the rear; that is, looking in the direction of from the top to the bottom of the sheet in Fig. 3. Fig. 6^A, is a detail view illustrating a feature of operation. Fig. 7, is a sectional view showing the

mechanism illustrated in Fig. 6. Fig. 8, is 55 an enlarged view of the package, and Fig. 9, is a detached view of the staple.

In the drawings 1 is a power shaft and it is a convenient source of power for the counter-shaft 2 which operates the mechanism about to be described. Rising from the bed or frame 3 of the machine is an overhanging head 4. The package *x* is presented beneath this head with the cord or twine *y* wrapped around it and crossed as shown in 60 Fig. 8; the ends *e* and *e'* of the cord or twine being held in the position shown in Fig. 8. The means whereby this is accomplished are 65 fully disclosed in our application above referred to and need not be described here and 70 the facts mentioned are recited merely to facilitate an understanding of the present invention.

On the face of the head 4 are arranged 75 two slides 5 and 6. These slides are each movable with respect to the head and the one in respect to the other. As shown the slide 5 works in ways in the head 4 and the slide 6 works in ways in the slide 5.

7 and 8 are a pair of jaws pivoted at 9 to 80 the slide 5, and the ends of these jaws are connected by pivotal links 10, which in their turn are pivoted at 11 to the slide 6. By moving the slides while in the same relative position it is possible to raise and lower the 85 jaws in open and closed position and by shifting the slides with respect to each other it is possible to open and close the jaws. The slides are worked in this way by means of mechanism which will now be described. 90

Referring to Fig. 4 on the back of each slide there is a rack 12 and for each rack there is a toothed sector 13. These sectors are mounted on shafts 14 and 15 sleeved together. At the end of these shafts are crank 95 arms 16 connected by links 17 with the pivotal followers of the grooved cams 18 and 19.

20 and 21 are feed rolls geared together and driven by gearing 22 from the counter-shaft 2. One of these feed rolls is provided 100 with a comparatively short projecting part 23 so that while they run continuously they feed the wire 24 intermittently. The wire is fed through a guide 25, Fig. 6, over an anvil 27 and under a holder 28. Both the anvil 27 and the holder 28 can be projected 105 and withdrawn with respect to the face of the head 4. This is accomplished by arms

29 on shafts 30 which are operated by grooved cams 31 on the shaft 2, through the intervention of links 33. The edge 34 of the arm 8 operates as a cutter when it passes the inner face of the guide 25 and cuts off an appropriate length of wire for making a staple.

35 is a lifter shown to comprise a fork having two pointed tines. This fork is carried by a curved arm 36 pivoted at 37 to a bracket carried by the head 4 and it is connected by a link 38 with a bracket 39 attached to the slide 5 so that the movement of the slide causes the fork to swing about its center into the position shown in Fig. 4 and into the position shown in Fig. 5 where it underlies the twine or cord *y*, lifting the same from the package or the wrapper of the package into position for receiving a clenched staple.

40 and 41, Fig. 6, are cutters pivoted as at 42 to a bracket carried by the head 4.

It may be said that the jaws 7 and 8 work in the plane of the dotted line *a—a* in Fig. 8, and that the cutting jaws work in the plane of the dotted line *b—b* in Fig. 8, so that the cutting jaws and stapling jaws are in planes at an inclination with each other. This is due to the fact that the staple is placed crosswise of the crossed twine or cord. The end *e* of the twine or cord should be cut straight across so as to leave its end in condition to be threaded through some appropriate piece of machinery, not material to this case. There is a tappet arm 43 which operates upon a spring-pressed tappet rod 44 to which the shanks of the cutting jaws 40 and 41 are pivoted by links 45.

46 are guides for the ends of the jaws 7 and 8.

47 shows the staple clenched with its ends overlapping and this overlapping is produced by the shape of the working parts 48 of the stapling jaws 7 and 8.

45 A description will now be given of the mode of operation of the machine. The package *x* is in the position indicated in the various figures and the ends *e*, *e'*, of the cord are held in the position shown in Fig. 8.

50 The wire is fed so as to lie between the anvil 27 and the holder 28. The part 34 of the jaw 8 cuts the wire off and the jaws 7 and 8 bend the wire around the anvil 27 in the form of an open ring in Fig. 6^A, the part 34, of the jaw 8, or more accurately, the lower right-hand corner of that jaw shown in section is about to cut off the wire 24, when the jaw is descending. It will be understood from that figure that the part 34 lies behind a laterally projecting flange which is broken away in Fig. 6^A. The anvil and holder are then withdrawn leaving the partially made staple held between the ends of the jaws 7 and 8. The jaws 7 and 8, carrying the open

65 staple, descend in the plane of the line *a—a*,

Fig. 8, putting the staple across the cord or twine and clenching it with its ends crossed, as shown in Fig. 9. These various movements are brought about by the mechanism which has already been described, 70 which includes the movement of the movable slides 5 and 6. The movement of these slides also causes the lifter 35 to get in under the twine or cord as shown in Fig. 5, and so lift it up into position for receiving 75 the staple. The movement of the slides also closes the cutters 40 and 41 and cuts the cord on the line *b—b* of Fig. 8. In this way the staple is very tightly applied to the cord or twine so that the latter is very firmly held. 80 The surface of the package or the wrapper around it is not torn or marred and the cord or twine is cut off in such a way that it can be readily threaded as in preparation for tying additional packages. Additionally the 85 staple is made in the course of the operation from a length of wire and is, it might be said, in the making properly placed in the stapling jaws. The operations described are repeatedly and satisfactorily performed and 90 the mechanism is simple and positive in action. The end of the wire 24, may butt into the left-hand side wall, Fig. 1, of the ways in the head 4, in order to help measure off a proper length of wire for a staple, or a 95 spring retracted stop 49, Fig. 6, may be employed. This stop 49, is pivoted as at 50 and normally held by a spring 51 against a stop pin 52 in the line of feed of the wire 24, so that when the end of the wire strikes 100 it the wire cannot be fed farther but may slip in the rolls 20 and 21. When the stapling jaws descend, the jaw 7 pushes and turns the stop 49 out of its way.

It will be obvious to those skilled in the 105 art that modifications may be made in details of construction and arrangement hence the invention is not limited to those matters nor to the precise embodiment of it selected for illustration, nor is the invention limited 110 in any way further than the prior state of the art and the appended claims may require.

What we claim is:

1. In a package twine fastening machine 115 the combination of stapling jaws adapted to clench a staple around the crossed twine, a twine lifter independently movable with respect to all said jaws and adapted to pass between the package and its crossed twine 120 to lift the latter into range of the staple, and means for operating said parts including mechanism for moving the lifter with respect to all the jaws, substantially as described.

2. In a package twine fastening machine the combination of a twine lifter consisting of a fork with pointed tines and adapted to pass between the package and its crossed twine, stapling jaws adapted to work be- 130

tween the tines and to apply and clench a staple to the twine, and means for operating said parts.

3. In a package twine fastening machine 5 the combination of a movable anvil and holder arranged in the path of stapling jaws, means for intermittently feeding wire between the anvil and holder, stapling jaws adapted to cut off a length of wire and to 10 form the same into an open staple, means for withdrawing the anvil and holder leaving the partly formed staple in the jaws, slides to which the jaws are connected, and means for differentially moving said slides to operate 15 said jaws and cause them to apply and clench the staple.
4. In a package twine fastening machine the combination of a head, slides each movable with respect to the head, stapling jaws 20 pivoted intermediate of their lengths to one of said slides, links connecting the shanks of the jaws with the other of the slides, and means for differentially moving the slides to open, close, project and retract said jaws.
- 25 5. In a package twine fastening machine the combination of pivotally connected stapling jaws, a movable slide to which said jaws are pivoted, a second movable slide, links connecting the shanks of the jaws with 30 the second slide, ways for said slides, means for feeding a wire across said ways beneath said jaws, an anvil below and a holder above the wire, means for differentially moving said slides to cause the jaws in open posi-

tion to cut the wire and bend it over the 35 anvil into an open ring, means for withdrawing the anvil and holder, and said slide moving means adapted to move the jaws and to thereafter cause them to clench the staple, substantially as described.

40 6. In a package twine fastening machine the combination of stapling jaws, a movable slide to which they are pivoted, a second movable slide having link connection with the shanks of the jaws, a pivoted twine 45 lifter, means interposed between the twine lifter and one of said slides whereby the lifter presents the twine to the stapling jaws, and means for actuating said parts, substantially as described.

50 7. In a package twine fastening machine the combination of slides each movable, stapling jaws pivoted to one of said slides, pivotal links between the shanks of the jaws and the other of the slides, cutting jaws 55 pivoted to one of said slides, a tappet rod linked to the shanks of the cutting jaws, a tappet arm on one of the slides for working said tappet rod, and means for differentially moving said slides to operate and 60 project and retract said jaws.

In testimony whereof we have hereunto signed our names.

MARTIN O. REHFUSS.
